FLAT PLATE PRESSING MACHINE FOR
FABRICSFred Hattersley Pickard, Roundhay, Leeds,
EnglandApplication June 23, 1934, Serial No. 732,141
In Great Britain June 26, 1933

9 Claims. (Cl. 26—38)

This invention relates to flat plate pressing machines for use in the finishing of textile fabrics, said machines being of the kind in which the material to be pressed is passed in a plurality of 5 layers or folds between press paper or other sheets suspended in each of the nips afforded by the superposed flat plates of the press, said press sheets, which serve to separate the layers or folds of material in each nip, extending beyond 10 opposite edges of the press plates and being supported at their opposite ends upon rods or the equivalent.

In machines of this kind as hitherto constructed the carrying rollers for the material to be 15 pressed and the press sheet rods or like supports associated with each nip of the press have been fixed in position, and in consequence the number of press plates or nips and the amount of total lift or movement of the press plates which could 20 be usefully employed in any press without tearing or subjecting the material and the press sheets to excessive tension have been limited.

According to the invention the carrying rollers and press sheet supporting rods or the equivalent 25 associated with the nips in machines of the kind set forth are adapted to move collectively more or less in unison with the plates of said nips so that both the material and the press sheets therein will not be subjected to undue tension during 30 the pressing operation.

Thus the two sets of carrying rollers and press sheet supporting rods, located one on the feeding side and one on the delivery side of each nip, are adapted to move toward each other or toward the 35 adjacent edges of the press plates during the rising thereof so as to slacken the material and press sheets sufficiently to allow for the lift of said plates without subjecting the material and press sheets to undue tension. In a modification the 40 carrying rollers and press sheets associated with each nip may be adapted to be moved vertically or horizontally in accordance with the movement of the plates affording said nip, and in this connection the carrying rollers and press sheet 45 supporting rods may be adapted to be operated by the lower plate of the nip, or other suitable means.

In either case the carrying rollers and rods would assume their normal positions when the 50 nips of the press are opened so that the material can be drawn through the nips and between the press sheets therein intermittently in predetermined lengths.

In order that the invention may be clearly 55 understood and readily carried into effect, the

same will now be more fully described with reference to the embodiments illustrated in the accompanying drawings; wherein:—

Figures 1 and 2 are similar fragmentary sectional elevations of a flat plate pressing machine for fabrics, Figure 1 illustrating the plates apart and Figure 2 showing the nips closed to press the fabrics. 5

Figures 3 and 4 are respectively similar views to Figures 1 and 2 but illustrate a modification. 10

Figures 5 and 6 are similar views to Figures 1 and 2 respectively but show a further modification.

Referring to Figures 1 and 2 of the drawings, the machine frames 1 have between them the upper press plate 2, and the ram 3 carries the bottom press plate 4, whilst there are three intermediate press plates 5. The pieces of material 6 after passing over feed rollers 7 on the machine frame 1 pass to and fro between carrying rollers 8 so that the layers or runs extend between the nips of the press. Each of the press plates 2, 4 and 5 is faced with press paper at 9, and the layers or runs of material 6 passed between each nip of the press are separated one from the other by 25 press paper sheets 9^x suspended from press sheet rods 10.

The two sets of carrying rollers 8 and associated press sheet rods 10, located one on the feeding side and one on the delivery side of each 30 nip, are mounted upon bearing blocks or brackets 11 which are freely pivoted at their upper ends to the machine frame 1 at 12 so as to be capable of a swinging movement toward and away from the press plates, whilst each of the depending 35 pivot brackets 11 is connected at its lower end by a pivoted connecting rod or link 13 to the lower press plate 4, so that as the latter rises the bearing blocks or brackets 11 will have an angular motion toward the press plates 2, 4 and 5, thereby 40 slackening the material 6 and press sheets 9^x sufficiently to allow for the lift of the press plates without subjecting the material 6 and press sheets 9^x to undue tension. When the ram 3 lowers and the nips open to release the material 6 and suspended press sheets 9^x, the brackets 11 move outward from the press plates and the material 6 is drawn therethrough ready for the next pressing operation. In this connection the lengths of material 6 are drawn off around take-off rollers 45 14 carried by the depending brackets 11 on the delivery side of the press, and the material 6 is preferably led off in a backward and upward direction as shown so as not to be subjected to any tensioning action by the take-off rollers 14 when 50

55

their carrying brackets 11 swing inward toward the nips. The carrying rollers 8 may be free-running rollers, preferably mounted in ball bearings, so that the cloth can be pulled through the open 5 nips in layers, or they may be geared together by spur pinions 15 (see Figure 1) carried by the depending pivot brackets 11, so as to constitute carrying rollers for the material 6, the drive for said gearing being taken from any convenient 10 running part of the press. Also the connecting rods or links may be adjustable for length say by means of turnbuckles 16 as shown, and they may be adjustably connected to the press plate or to the pivoted bearing blocks or brackets 11 so 15 as to enable the movement imparted to the carrying rollers 8 and rods 10 to be varied to suit the lift of the press.

Referring now to Figures 3 and 4 of the drawings, in which like references to those in Figures 20 1 and 2 indicate like or analogous parts, the two sets of carrying rollers 8 and associated press sheet rods 10 are mounted upon members 11 vertically slidable in guides 18 on the frame 1, the lower end of each of said slidable members being connected by a link 19 to the free end of a lever 20 pivoted to the frame 1. Connecting rods or links 13, which are adjustable in length by means of turnbuckles 16, serve to connect the lower press plate 4 to the free ends of the levers 20 at 25 either side, the arrangement being such that as the said lower press plate 4 is raised during the pressing operation the slidable members 11, carrying the rollers 8 and rods 10, are raised in unison as shown in Figure 4, so as to prevent 30 undue tension being put upon the material 6 and press sheets 9.

In the embodiment illustrated in Figures 5 and 6, in which like references to those in Figures 1 and 2 also indicate like parts, the rollers 8 and 40 associated rods 10 are mounted upon members 21 slidable in horizontal guides 22 and loaded by springs 23 which tend to keep said members 21 apart. Each member 21 is adapted to be moved in its guides 22 against the action of the springs 45 23 by means of cam levers or bell cranks 24 pivoted to the frame 1 and coupled together by a link 25. The cam levers or bell cranks 24 are actuated by levers 26 connected to the lower cam lever or bell crank 24 at each side and having 50 pin and slot connections 27 with the lower press plate 4, the arrangement being such that as the latter rises the members 21 with their rollers 8 and rods 10 are moved towards one another against the action of the springs 23 so as to prevent 55 undue tension upon the material 6 and press sheets 9.

It will be understood that the invention may be applied to presses having any number of plates within practical limits.

60 I am aware it has before been proposed in a press in which the press sheets are freely suspended from the press plates to mount the carrying rollers on pivoted arms at opposite sides of the nips, said arms being connected by links to the bottom press plate so as to swing towards the nips and thereby slacken the material as the press plates rise.

I claim:

1. In a flat plate pressing machine, a frame 70 having spaced standards, press plates positioned between said standards, cloth carrying rollers and press sheet supporting rods carried by said standards, and means for collectively moving the carrying rolls and supporting rods in unison with 75 said press plates whereby the material and the

press sheets will not be subjected to undue tension during the pressing operation.

2. In a flat plate pressing machine, a frame having spaced standards, vertically movable press plates positioned between said standards, two sets of carrying rollers and press sheet supporting rods, located one on the feeding side and one on the delivery side of said press plates, and means for moving each set toward each other and toward the adjacent edges of the press plates during the rising of said plates whereby the material and press sheets are sufficiently slackened to allow for the lift. 5

3. In a flat plate pressing machine, a frame having spaced standards, bearing brackets movably mounted upon said standards, carrying rollers and associated press sheet supporting rods mounted on said bearing brackets, vertically movable press plates positioned between said standards, and separate means connecting each bracket with one of said press plates whereby as said press plate is moved up and down said bearing brackets will move in unison therewith and prevent undue tension between the material and press sheets. 15

4. In a flat plate pressing machine, a frame having spaced standards, bearing brackets pivotally mounted at their upper ends upon said standards, carrying rollers and associated press sheet supporting rods mounted on said bearing brackets, vertically movable press plates positioned between said standards, and separate means connecting each bracket with one of said press plates whereby as said press plate is moved up and down said bearing brackets will have 30 angular movement toward and away from the press plates. 20

5. In a flat plate pressing machine, a frame having spaced standards, bearing brackets pivotally mounted at their upper ends upon said standards, carrying rollers and associated press sheet supporting rods mounted on said bearing brackets, vertically movable press plates positioned between said standards, and connecting rods connecting the lower ends of said brackets to the lowermost 40 press plate whereby as said press plate is moved up and down said bearing brackets will have angular movement toward and away from the press plates. 45

6. In a flat plate pressing machine, a frame 50 having spaced standards, bearing brackets pivotally mounted at their upper ends upon said standards, carrying rollers and associated press sheet supporting rods mounted on said bearing brackets, vertically movable press plates positioned between said standards, and adjustable connecting rods connecting the lower ends of said brackets to the lowermost press plate whereby as said press plate is moved up and down said bearing brackets will have angular movement 55 toward and away from the press plates.

7. In a flat plate pressing machine a frame having spaced standards, vertically movable press plates positioned between said standards, two sets of carrying rollers and press sheet supporting rods, located one on the feeding side and one on the delivery side of said press plates, and means for moving each set vertically during the rising of the press plates whereby the material and press sheets are sufficiently slackened to allow 60 for the lift. 65

8. In a flat plate pressing machine, a frame having spaced standards, bearing brackets slidably mounted upon said standards, carrying rollers and associated press sheet supporting rods 70 75

mounted on said bearing brackets, vertically movable press plates positioned between said standards, and separate means connecting each bracket with one of said press plates whereby as said press plate is moved up and down said bearing brackets will move in unison therewith and prevent undue tension between the material and press sheets.

9. In a flat plate pressing machine, a frame having spaced standards provided with vertical

guideways, bearing brackets slidably mounted in said guideways, carrying rollers and associated press sheet supporting rods mounted on said bearing brackets, vertically movable press plates positioned between said standards, and means for moving said brackets vertically during the rising of the press plates whereby the material and press sheets are sufficiently slackened to allow for the lift. 5

FRED HATTERSLEY PICKARD. 10
